UNITED STATES PATENT OFFICE.

GEORGE J. ARFSTEN, OF DENVER, COLORADO.

TELEPHONE-RECEIVER ATTACHMENT.

1,123,654.

Specification of Letters Patent.

Patented Jan. 5, 1915.

Application filed April 20, 1914. Serial No. 833,247.

To all whom it may concern:

Be it known that I, GEORGE J. ARFSTEN, a citizen of the United States, residing at Denver, in the county of Denver and State 5 of Colorado, have invented a new and useful Telephone-Receiver Attachment, of which the following is a specification.

The present invention relates to improvements in telephone receiver attachments, one 10 object of the invention being the provision of a means whereby a tablet of sanitary paper is properly attached to the ear engaging portion of the receiver, so that each time the receiver is used, the user may remove a 15 sheet of paper and thereby present a clean surface to the next user.

A further object of the present invention, is the provision of a novel supporting means for carrying the tablet of paper, and for 20 disposing the same so that the aperture therethrough will be disposed coaxially with the aperture through the removable cap of the receiver.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the drawings Figure 1 is a side elevation of the ear engaging portion of the receiver with the present attachment applied, the tablet being shown in cross section. Fig. 2 is a rear elevation of the ear engaging portion of the receiver with the present attachment in place. Fig. 3 is a perspective view of the tablet carrying member and clamp of the present attachment.

Referring to the drawings, R designates the receiver, which has disposed about the 45 reduced portion at the rear of the ear engaging portion of the receiver, the open clamping band 1, having the two apertured terminals 2 for the reception of the clamping screw 3. Two diverging arms 4 are carried 50 by the band 1 at diametrically opposite points, the outer terminals of such arms 4 being constructed to terminate at a point at the rear of the removable cap C of the receiver at which point, the hinges 5 properly

connect for swinging movement the two arms 55 6. The outer ends of the arms 6 are in-turned as at 7 so that such arms may be projected through the apertures 8 of the relatively stiff plate 9 so as to engage the inner side thereof and thus support the tablet 11 60 in proper position, so that the outside sheet 12 of said tablet will be disposed in ear engaging position when the receiver is placed in use. The supporting board 9 and the tablet are provided respectively with the apertures 10 and 13, such apertures being disposed coaxially with the aperture (not shown) of the receiver cap C.

The sheets 12 of the tablet may be attached in any well known manner, but are 70 preferably attached at the reduced portions 14 so that the same may be readily removed a sheet at a time to thus present a clean sheet to the ear of the user.

By attaching the sheets of the tablet at 75 diametrically opposite points about the reduced portion as at 14, the free edges thereof are readily engaged by the finger of the user and thus each sheet is quickly removed to 80 present a clean sheet.

What is claimed is:

1. A sanitary attachment for telephone receivers, comprising a plurality of sheets in the form of a pad provided with a central opening therethrough, said pad having a 85 stiff back and such back being provided with a plurality of openings therethrough, a receiver gripping clamp, a plurality of arms carried by the clamp, and a hinged member having a hooked terminal connected to each 90 arm for disposition in one of the openings of the stiff back, whereby the pad is held relatively to the receiver.

2. A sanitary attachment for telephone receivers, comprising a pad provided with a 95 central opening therethrough, said pad having a stiff back and such back being provided with two diametrically disposed openings therethrough, a receiver gripping clamp, two arms carried by the clamp, and a 100 hinged member having a hooked terminal connected to each arm for disposition in one of the openings of the stiff back, whereby the pad is held relatively to the receiver.

3. A sanitary pad carrying device for telephone receivers, including an open band for disposition upon the handle of the receiver, two outwardly curved arms attached

to the band at diametrically opposite points and at points substantially at right angles to the opening of the band, and two L-shaped members hingedly connected to the terminals of the arms with the hooks disposed toward each other.

In testimony that I claim the foregoing as

my own, I have hereto affixed my signature in the presence of two witnesses.

GEORGE J. ARFSTEN.
